TIPPING ATTACHMENT FOR CLOTH EMBOSsing MACHINES

Werner P. Rose, Oakland, N. J.

Application April 14, 1954, Serial No. 423,099

2 Claims. (Cl. 118—44)

This invention relates to an ink or pigment tipping and/or inlay attachment for embossing calenders to impart ink and coloring pigment to the embossed material such as cloth, fabric or plastic sheets.

It is the principal object of the present invention to provide a tipping or inlaying attachment for a sheet material embossing calender so that the coloring of the embossed cloth fabric or plastic is effected at the time of the embossing whereby tipping or inlaying of the embossed material will be effected while still upon the actual embossing roll, and in true alignment therewith with a firm, even and level inking plane available because the paper backing roll pattern is still backed up and is still pressed into the raised portion of the embossed material in contrast to the spongey, uneven and bumpy inking plane which must be used when tipping is done after the material has been removed from the paper backing roll.

It is another object of the invention to convert a material embossing calender into a combined embossing calender and tipping or inlaying machine by a tipping or inlaying attachment adapted to be secured between the sides of the standard cloth embossing calender machine.

It is another object of the invention to provide an ink tipping and/or inlay attachment for material embossing machines that is adapted to be located at different elevations on the embossing machine frame to engage either the large embossing roller or the cooperating indented press roller whereby to provide inking or coloring on either the projected embossings of the material from the paper roll or upon the female die roll to effect inlay coloring in the unembossed portions of the material or by a combination with the use of two tipping attachments to effect the coloring of the embossed portions and the unembossed portions of the cloth together.

It is another object of the invention to provide a tipping and/or inlay attachment for material embossing machines wherein two such attachments are provided on the machine at different elevations wherein their ink or coloring rollers engaging with the embossed material are relieved to skip or leave certain of the embossed portions uninked while inking other of the embossed portions and wherein the uninked embossed portions leaving the first tipping attachment will be inked by the second tipping attachment with another color while skipping the already inked or colored embossed portions inked by the first tipping attachment whereby to provide a multi-colored tipped embossed cloth.

It is another object of the invention to provide a tipping and/or inlay attachment for material embossing machines employing a series of ink pick up rolls, the first dipping into an ink tray and transferring to a second roll and this second roll finally transferring the ink to the work engaging roll wherein an adjustment of each of the rolls can be effected relative to each other by adjusting screws and the inking rolls are driven by gearing connecting the rolls together, the intermediate roll being power driven with a variable speed drive mechanism whereby the sur-

face speed of the work engaging roll can be regulated according to the surface speed of travel of the embossed cloth.

It is another object of the invention to provide a tipping and/or inlay attachment for material embossing machines which has independent screws for individually adjusting the rollers and the attachment is so mounted that it may be quickly adjusted as a unit and wherein once the adjustment of the rollers is made relative to each other they need not be altered in order to remove the rollers from their work engaging position by a simple pulling of a lever wherein adjustment can be effected between the operating lever and the frame carrying the rollers in order to quickly effect the proper engaging contact of the work engaging roll with the embossed portions of the material so as to avoid blistering of the synthetic rubber on the work engaging roll should the entire machine be stopped and also to avoid loss of improperly tipped or inlayed cloth due to delay in readjustment of the work engaging roll.

Other objects of the invention are to provide a tipping attachment sheet for material embossing machines which is of simple construction, inexpensive to manufacture, has a minimum number of parts, easy to install upon the embossing machine and adjust relative thereto, compact and consumes little space, durable, of long life, effective in use and efficient in operation.

For other objects and for a better understanding of the invention, reference may be had to the following detailed description taken in connection with the accompanying drawing in which:

Figure 1 is a fragmentary vertical sectional view of a material embossing calender with one attachment of the present invention attached thereto for a tipping operation with the cloth riding thereover, the paper backing roll, and with illustrations showing another attachment located at the upper part of the machine for inlaying operation with the female press roll and another tipping attachment at the lower part of the machine when taken with the one attachment for effecting a second tipping operation upon the cloth riding over the paper backing roll;

Fig. 2 is an end elevational view of the material embossing calender and of the one tipping attachment attached thereto with its driving mechanism thereon;

Fig. 3 is an enlarged vertical sectional view looking generally upon the frame of the tipping attachment which supports the inking rolls in an adjustable manner and as viewed generally on line 3—3 of Fig. 2;

Fig. 4 is a vertical sectional view taken through one end of the tipping attachment frame as viewed generally on line 4—4 of Fig. 3;

Fig. 5 is a fragmentary sectional view of a slightly modified form of the invention with illustration being made of the inking roller of the attachment being relieved to permit the escape of certain of the embossed portions of the material as when a multiple color tipping operation is effected upon the material by two or more tipping attachments one mounted above the other or even in a circular arrangement around the embossing roll so as to accommodate a greater number of such attachments.

Fig. 6 is a fragmentary perspective view of one side of the embossing machine wherein two attachments arranged for multiple color tipping operations are respectively drivingly connected to a large drive gear on the paper roll by gears, one of which being an adjustable gear so that one of the attachments can be adjusted relative to the other;

Fig. 7 is an enlarged sectional view of the adjustable gear of the one tipping attachment as viewed generally on line 7—7 of Fig. 6; and

Fig. 8 is a fragmentary perspective view of one end

of the attachment showing the eccentric means including the lever for moving the inking rollers into and out of their working positions as a unit and without having to effect the adjustment of the individual rollers.

Referring now particularly to Figs. 1 and 2, there is shown a sheet material embossing calender indicated generally at 15 and having side frame members 16 and 17 at the opposite sides of the calender and joined together by appropriate tie bars 18 located at different stations along the length of the machine. Mounted on the side frames 16 and 17 are respectively heavy bearing members 19 in which shaft ends 20 and 21 of a large diameter paper backing roll 22 are journaled to support the paper backing roll 22 between the side frames 16 and 17 of the machine. This paper backing roll 22 is driven by appropriate power gearing, not shown, to cause the passage of cloth or fabric 24 through the calender. This paper roll 22 has a thick paper layer 25 against which a steel engraved female embossing press roll 26 is empressed to effect the formation of complementary male projections 27 upon the paper layer 24 which will conform to indentations 28 in the engraved embossing or press roll 26. The paper roll 22 may also be formed with a backing layer of synthetic rubber, plastic, synthetic compounds, nylon, "Daeron," cotton, felt, wool or wood. The cloth material 24 in passing between these rolls is thereby embossed. Appropriate heating means is provided in the embossing or press roll 26 to properly treat the cloth and give to it the embossed effect.

The embossing roll 26 is journaled between arms 29 that are respectively pivoted at 29' upon the respective side frame members 16 and 17 of the calender. These arms 29 are guided against lateral displacement while being pivoted, by upright guide pins 31 fixed to the respective side frame members by respective nuts 32 and extending upwardly through slots 31' in the ends of arms 29. A piston rod 33 is connected to each arm 29 by a set collar 34 engaging with the upper end of the member 29 and with a power cylinder device 35 anchored to a bottom bracket 36 by a pin 37. As hydraulic or pneumatic pressure is supplied to the device 35, the arms 29 are brought down and the embossing or press roll 26 is brought into tight engagement with the cloth 24 and paper backing roll 25.

On one end of the calender are brackets 38 that support a cloth supply roll 39 from which cloth 24 is taken to be embossed. This cloth travels upwardly and forwardly over three small tension rolls 40, 41 and 42 before reaching the large diameter paper backing roll 22.

With the embossing or press roll 26 in place upon the paper roll 22, the cloth is embossed as it is passed between the rolls and continues to run over the paper backing roll 22 and past an ink or color tipping attachment 43 constructed according to the present invention. From the paper backing roll 22 the cloth passes rearwardly over a small roll 44, upwardly over a large drying roll 45, forwardly over a small roll 46 and then downwardly on to a cloth collecting roll 47 releasably retained on supporting brackets 48 and 49 on the respective side frames 16 and 17 of the calender at the opposite end thereof from the cloth supply roll 39.

The tipping attachment 43 is supported between the side frame members 16 and 17 at the cloth collecting end of the calender. To the side frame member 16 there is secured a rearwardly-extending, angle section supporting bracket 50 and to the side member 17 there is secured an oppositely turned, rearwardly-extending angle section supporting bracket 51, Fig. 2. The bracket 50 supports a journal bearing 52, and the bracket 51 supports a journal bearing 53. A shaft 54 journaled between the bearings 52 and 53 and just inwardly of the supporting brackets 50 and 51 at the opposite ends thereof are respectively secured eccentric cams 55 and 56 lying respectively within operating follower rings 57 and 58. A hand lever arm 59 is secured to one end of the shaft 54 and when

used to rotate the shaft 54, the follower rings 57 and 58 will be caused to move either forwardly or rearwardly.

Each follower ring 57 or 58 has an internally-threaded portion 60, Fig. 8, into which is threaded a threaded shaft 61 having threads cut in one direction and when adjusted is locked to the portion 60 by a lock nut 62. A turn-buckle sleeve 63 is secured to the opposite end of the shaft 61 and to a threaded shaft 64 having threads cut in the opposite direction of the threads of the shaft 61 and which is secured, when adjusted, to a slide bar 65 by a lock nut 66.

The slide bar 65 is slidable in an inverted channel guide 67 having opposing guide projections 68 and 69 lying respectively in cooperating grooves of the slide 65, Fig. 8. This inverted channel guide 67 is secured to an angle section supporting bracket 70 that is fixed to the side frame member 16 or 17. The supporting brackets 50 and 51 are respectively fixed to the angle section brackets 70 in back to back relationship and are secured therewith as a unit to the side frame member 16 or 17.

Slidable along the angle section supporting bracket 70 is a depending bracket 71 of Z-section that has a horizontal portion 72 that is welded to the bottom of the slide 65 and which rides over an inwardly extending portion 73 of the angle section supporting bracket 70.

The inverted guideway channel guide 67 has spaced elongated slots 75 and 76, Fig. 3, into which extend respectively screws 77 and 78 that connect a bottom side portion 79 of an up-standing guide frame 80 with the slide 65 within the inverted channel guide 67 so that as the slide 65 is moved, the guide frame member 80 is moved.

The guide frame 80 has a top side portion 81 and an intermediate guide portion 82 lying between the bottom side portion 79 and the top side portion 81, Fig. 3. The guide frame 80 is integrally closed at one end and the other end is closed by vertically-extending lower and upper plates 83 and 84 through which there extend respectively adjusting screws 85 and 86 that respectively have hand adjusting wheels 87 and 88 that are respectively retained by pins 87' and 88'.

The adjusting screw 85 is connected to a slide support 89 that has a retaining sleeve 90 secured thereto by a spring ring 91 and supports a bearing sleeve 92, Fig. 4. A roller shaft 93 of intermediate rubber ink transfer roll 94 is journaled in the bearing sleeve 92. By turning the adjusting screw 85, slide 89 and one end of the ink transfer roll 94 is adjusted in the frame 80. A similar adjustment may be made at the opposite side of the attachment.

The adjusting screw 86 is connected to a slide support 95 adjustable along guide portions 81 and 82 above the slide support 89 and which has a retaining sleeve 96, Figs. 3 and 4, secured by a spring ring 97 to the slide 95 and that supports a bearing sleeve 98 in which is journaled a shaft 99 of a top-delivery synthetic rubber or plastic tipping roll 100 adapted to engage the raised or embossed portions of the cloth as the embossed cloth moves past the tipping attachment 43. The inking roll 100 engages with the intermediate transfer roll 94 to receive ink or color pigment therefrom.

Below the intermediate ink roll 94 is a knurled or engraved ink pick-up metal roll 102 that dips in a tray 103 to pick up the ink or color pigment used for the tipping of the embossed cloth, Figs. 3 and 8. The tray 103 is supported on a horizontal portion 104 of the depending Z-bracket 71 by a vertical adjustment screw 105 turnable through a depending nut 106 fixed to the bracket portion 104 and journaled in a depending boss 107 on the bottom of the tray 103. The adjusting screw 105 has a handwheel knob 108 by which the screw 105 is turned. The tray contains the ink or pigment to be transferred to the embossed portions of the cloth 24. With a given depth of ink or color pigment in the tray, the roll 102 can be adjusted to press more or less against the rubber

transfer roll so as to impart more or less ink to it. A similar adjustment may be made at the opposite side of the attachment.

On each end of the tray 103 is a bracket 109 that has an open vertical slot 110 therein for receiving a shaft end 111 in which the pick-up roll 102 is disposed, Fig. 3. Since the pick-up roll 102 is carried by the tray 103, it will be adjusted with the tray toward and away from the intermediate transfer roll 94.

To effect equal distribution of the ink or color pigment upon pick up roll 102, a wiper blade 113 engages the surface of the roll 102, Figs. 3 and 8. This wiper 113 is held between two retaining plates 114 and 115 and secured together by nut and bolt means 116. On the Z-bracket 71 there is fixed a pivot pin 118 that carries a depending pivot arm 119 that is adjusted by an adjusting screw 120 threaded through a lug portion 121 on the Z-bracket 71 and which has a hand turning knob 122. The top plate that holds the wiper blade 113 has a bearing portion 123 that extends over the pin 118 and is connected by pin 123' to arm 119 so that movement of the arm 119 will cause movement of the wiper 113 and change the point of engagement with the wiper upon the pick up roll 102.

As an alternative means for holding the wiper on the roll, there is provided a weight arrangement to be presently described. Mounted on frames 80 at the tops thereof are respectively upwardly and rearwardly inclined brackets 124 and 125, Figs. 1 and 2, and between these brackets 124 and 125 is fixed a shaft 127 on which are journaled axially-spaced pulleys 128 and 129. Extending rearwardly from the wiper retaining plate 114 are spaced rearwardly-extending hook arms 130 and 131 to which there are respectively connected pulley cables 132 and 133 having respectively weights 134 and 135. These weights act upon the wiper blade 113 in such a manner as to hold the same tight against the ink pick up roll 102. For this action the pins 123' will have been removed, and the adjusting screw will have been disengaged from the pivot arm 119.

At times the wiper blade 113 is positioned on the bottom side of pick up roll 102 in the reverse manner of the showing in Fig. 3 and in order that the weights may be applied properly to maintain the wiper in this position, the spaced hooks 130, 131 are fastened to the retaining plate 114 in the reverse manner from that shown in Figs. 1 and 2, and the weights 134 and 135 are hung directly therefrom whereby the edge of the wiper element 113 will be held against the underside of the ink pick up roll 102. In this position of the blade, ink is not put into the pan but is poured between the blade and the knurled or engraved roll and is prevented from flowing rapidly out into the pan by means of a felt pad or dam cut out in a V-shape to fit between the blade and the roll and held in place by a brass clamp with thumb screw fastening to the blade at each end thereof. Several of these dams can be clamped in position on the blade and different colored inks can be poured between them so as to give a multi-colored striped effect to the tipping or inlaying.

The inking rolls of the attachment are driven by a variable speed drive mechanism 137, Figs. 1 and 2, having an electric motor 138, a control handle 139 and a reduction gear mechanism 140 having a pulley 141 that is connected by a multi-piece belt 142 with a pulley 143 on the shaft 93 of the transfer roll 94. This shaft 93 has a driving gear 144 that is meshed with a gear 145 fixed to shaft 111 of the pick up roll 102, Fig. 2, and the gear 146 fixed to shaft 99 of the rubber tipping roll 100. By turning the control lever 139 the speed of the tipping roll 100 will be altered so that the surface speed of the tipping roll 100 can be run opposed or in the same direction as, and synchronized with, or at a greater or less speed than the surface of the paper backing roll 24 having the embossing projections 27 as desired. By operating the hand wheels 75

87 and 88, the rolls 94 and 100 can be adjusted to different forward and rearward locations in order to properly have the tipping roll 100 engage the projections 27 and the cloth running thereover. The ink pick up roll 102 is adjusted from underneath the attachment by the hand wheel 108. Once the proper adjustment of the rolls has been made, the rolls can be moved into and out of the tipping position as a unit by the lever 59 without effecting their adjustment. It will thus be seen that the tipping attachment 43, as applied to the cloth calender as shown in Figs. 1 and 2, has its own independent driving mechanism. The tipping attachment, as set up in this manner, merely has to be adapted for the application of ink to the cloth. By pulling any one or all of the levers 59 of the tipping units, any one or all of the units can be disabled or dispensed with.

To provide upon the cloth 24 both the coloring of the projections and of a color inlay or ground, an inlay attachment 150 of like construction to the attachment 43, Fig. 1, is similarly connected between the side frames of the calender so that its surface engaging or tipping roll 151 will deposit ink or color pigment on the surface of the embossed press roll 26 and free of the recesses 28 so that this ink as the press roll 26 revolves is deposited by the press roll upon one side of the cloth 24. The tipping attachment 43 covers the embossed projections of the cloth with further ink which may be of different color. The variable speed drive mechanism 137 has a double pulley so that the inlay attachment 150 is driven by a pulley belt 152 extending to the attachment 150. If it is desired to have only the inlay coloring from the attachment 150, the tipping roll 100 of the attachment 43 can be withdrawn by merely pulling the lever 59. This can be effected at the will of the operator and the attachment 150 will be similarly provided with a lever 59 so that it can also be withdrawn thereby and selective operations of the attachments can be effected.

To color the embossed portions of the cloth with two or more different colors, a pick up roll 100' of the attachment 43 is shown in Fig. 5 provided with recesses 155 so that certain of the embossed portions of the cloth escape tipping while other embossed portions will be tipped as indicated at 156. Another tipping attachment indicated generally at 157 has a tipping roll 158 similarly provided with recesses 159. These recesses 159 are arranged to permit the escape of the embossed projections tipped by the roll 100' which have been provided on the attachment 43 and tip the remaining embossed projections. In a similar manner two or more different colors may be inlaid in the ground or unembossed portions of the cloth material likewise using a gearing arrangement as described in the next two paragraphs.

When the tipping or inlay attachment 43 and 157 are used in this manner to skip certain embossed projections of the cloth and to give different coloring to the skipped projections, a drive arrangement permitting the adjustment of the tipping roll of one attachment relative to the tipping roll of the other attachment is needed. The shaft end 20 of the paper roll 22 is provided with a large drive gear 160, Fig. 6. The tipping attachment 43 is provided with a small gear 161 on its shaft 93 of the transfer roll 94 which engages large gear 160 to be driven thereby. The belt from the variable speed drive mechanism 137 will have been disengaged and the operation of the tipping attachment 43 will now be wholly driven from the large gear 160. An adjustable gear 162 is provided on a shaft extension 163 of a transfer roll 94' of the attachment 157. This adjustable gear 162 is constructed as shown in Fig. 7 and comprises a sleeve 164 that is keyed to the shaft 163 by means of a key fitting keyway 165. The sleeve 164 is held against axial displacement on the shaft 163 by a set screw 166. A set collar 167 is fixed by a set screw 168 to the sleeve 164. Against this set collar 167 is rested a small gear 169 that meshes with the large gear 160 of the paper roll.

Fixed to this small gear 169 by screws 171 is a support

ing plate 172. This plate 172 has two spaced lugs 173 and 174 between which is journalled a worm gear 175 than can be adjusted or turned by inserting a wrench into a wrench opening 176. This worm gear 175 meshes with a worm wheel 177 that is keyed by a key 178 to a sleeve 164. Since the sleeve 164 is fixed to the shaft 163 a turning of the worm gear 175 will effect a shifting of the tipping roll 100' of the tipping attachment so that its recesses 155' can be aligned and accurately registered to properly receive the already tipped embossed projections of the cloth.

The tipping attachments can accordingly be outwardly moved as a unit by the hand lever 59 as above explained and the gears 161 and 162 disengaged from the gear 160. The tipping attachments are similarly constructed throughout except for the differences in the driving of the same and in the recesses of the tipping rolls as already set forth.

It will be apparent that there has been provided a tipping attachment adapted for connection to a cloth embossing calender to provide a combined calender and tipping machine for inking the embossed projections or the inlay portions of the cloth while the cloth is firmly retained on the machine and done on the same machine by which the cloth is embossed.

It will be further apparent that the attachment is provided for adjustment of all of its inking rolls, the ink containing tray, the wiper and that provision has been provided, once the rolls have been properly set, for the movement of the attachment as a unit into and out of its tipping position.

While various changes may be made in the detail construction, it shall be understood that such changes shall be within the spirit and scope of the present invention as defined by the appended claims.

What is claimed is:

1. An ink tipping or inlaying attachment for a sheet material embossing calender adapted to be extended between the side frames of the calender comprising brackets of angle section adapted to be opposingly secured to the side frames and respectively having horizontal inwardly extending supporting portions, an inverted channel shaped member fixed to each bracket with its lower edges spaced above the horizontal portion thereof, a slide operable in said inverted channel member, a bracket of Z-shaped section having a horizontal portion under the inverted channel and supported on the horizontal portion of the angle section bracket and secured to the bottom of the slide, tray means supported on the Z-shaped brackets for vertical adjustment with respect thereto, a frame 40

having three horizontally extending guide portions, said channel member having elongated slot means therein and fastening members extending between the bottom horizontal portion of the frame, through the slot means and the slide whereby the frame is movable with said slide, two roll supporting slides respectively connected between horizontal portions of the frame and adjusting screws connected to the respective slides of the frames for effecting the fore and aft adjustment of the slides, rollers engaging with one another and with the pick-up roller within the tray, extending between the slides of the frames and transversely of the calender, and extension on each angle section bracket, a shaft journalled between the extensions and having a hand lever thereon, cams respectively fixed to the shaft adjacent the respective extensions, a cam follower for each cam, and a turn buckle connection between the cam follower and one end of the main slide whereby the attachment rolls can be withdrawn from the embossing roll of the calender as a unit.

2. A combined cloth embossing and ink tipping machine comprising an engraved embossing press roll and a backing roll having a complementary raised pattern, a tipping attachment having a tipping roll with recesses therein to escape the tipping of certain of the embossed portions of the cloth, a second tipping attachment spaced from the first tipping attachment and having recesses therein for permitting the escape of the projections tipped by the first attachment and effecting the tipping of the remaining projections, said backing roll having a large gear thereon, one of the said tipping attachments having a gear meshing with the large gear to be driven by the same and the other of said tipping attachments having an adjustable gear meshing with the large gear whereby adjustment of the tipping roll of one machine can be effected relative to the recessed tipping roll of the other attachment.
